SOLE LAYING MACHINE

Filed April 3, 1929

UNITED STATES PATENT OFFICE

SIDNEY J. FINN, OF BEVERLY, MASSACHUSETTS, ASSIGNOR TO UNITED SHOE MACHINERY CORPORATION, OF PATERSON, NEW JERSEY, A CORPORATION OF NEW JERSEY

SOLE LAYING MACHINE

Application filed April 3, 1929. Serial No. 352,279.

This invention relates to sole laying machines for boots and shoes and is herein illustrated as embodied in a machine of the type disclosed in Letters Patent No. 1,495,163 granted May 27, 1924 upon an application filed in the name of Louis A. Casgrain.

In machines of the type referred to a lasted shoe with a rubber sole lightly adhering to it in proper position on its bottom is placed upon a rubber diaphragm which forms the upper wall of a pressure box. A jack then operates to push the shoe part way into the box and to hold it in this position while water under pressure is forced into the box to wrap the diaphragm about the lower portion of the shoe and thereby lay the sole,—that is, press it firmly into place. The pressure of water used is considerable and would be sufficient to cause the diaphragm to balloon up about the sides of the shoe and very possibly under such circumstances to burst. In order to guard against any considerable ballooning or upward deflection of the diaphragm, machines of the above-mentioned type have been provided with a plate which is located above the rubber diaphragm and has in it a substantially sole-shaped opening. It is upon the portion of the diaphragm exposed by this opening that the shoe is placed, and it is through this opening that the lower portion of the shoe is pushed by the jack. When water under pressure is forced into the pressure box, the plate prevents any considerable ballooning of the diaphragm and limits the flexing of the diaphragm to the narrow space between the edge of the opening in the plate and the adjacent sides of the shoe. A given plate is intended for use with shoes which are of a given size or which at least do not differ greatly in size; and there is provided with the machine a series of interchangeable plates having in them openings of graduated sizes.

According to one feature of the invention interchangeable plates such as these are done away with and there is provided a plurality of members adapted to enclose a suitably shaped opening through which a shoe may pass, said members being adjustable to

vary the size of the opening, and means for locking the members in adjusted position. In the illustrated construction these members take the form of four plates which are slidably mounted above the diaphragm and enclose an elongated opening having ends which are rounded. The illustrated plates are arranged to be adjusted in pairs by turning two hand wheels so as to vary the size of the opening while maintaining its shape substantially unchanged and to be locked in adjusted position. With this construction the size of the opening may be quickly changed to accommodate shoes of different sizes.

This and other features of the invention including certain details of construction and combinations of parts will be described as embodied in an illustrative machine and pointed out in the appended claims.

Referring now to the accompanying drawing,

Fig. 1 is a perspective of part of a sole laying machine in which the present invention is embodied, and

Fig. 2 is a partial plan of the plates upon an enlarged scale showing more particularly the mechanism for adjusting the plates.

Referring first to Fig. 1, the sole laying machine, a portion of which is shown, is or may be, except for certain features which will be pointed out later, substantially the same as the machine shown in Letters Patent No. 1,495,163 which has been referred to above. The machine comprises a pressure box 3 fastened to a pedestal 5 and having an upper wall consisting of a flexible rubber diaphragm 7, which is not normally flat but is curved in the direction of its length so that its middle is at a level somewhat lower than that of its ends. This diaphragm rests on top of the upright walls of the box and is clamped in place by a cover 9 and bolts, four of which are indicated at 11. In the operation of the machine, a lasted shoe with an unvulcanized rubber sole lightly attached to its bottom is placed upon the diaphragm and power is applied to the machine to cause it to operate in the following manner. A jack having a front post 13 and a rear post 15 is swung over the lasted shoe and a rear post 15 is swung over the lasted shoe.

shoe and by engagement respectively with the toe portion of the shoe and the crown of the last, pushes the shoe part way down into the pressure box, thereby bending the diaphragm 5 downward. Water under pressure is next forced into the box to wrap the diaphragm about the lower portion of the shoe and thereby to press the sole firmly into place. Water is then withdrawn from the pressure box, the 10 jack swings upward and to one side into the position shown; and the machine comes to rest. As thus far described the machine is or may be substantially the same as the machine of the patent and will not be further described since the details of its construction 15 per se form no part of the present invention.

The cap or cover 9, which has a comparatively large elongated opening through its longitudinal middle is provided with two 20 pairs of guideways the members of each pair of which converge from the respective ends of the cap toward the middle thereof. Mounted in the converging guideways 17, 19 at the front end of the cap is a pair of plates 21, 23, 25 the outer edge of the plate 21 being slidably mounted in the guideway 17, while the outer edge of the plate 23 is slidably mounted in the guideway 19. The inner or adjacent edges of the plates are complementary to each 30 other and cooperate to produce between them a generally U-shaped recess. Cut in the plate 23 is a slot 25 which extends transversely of the pressure box; and a bolt 27 fast to the plate 21 extends up through the slot and carries a washer 29 and a nut 31, the purpose of 35 this slip-connection between the plates being to hold them in contact while permitting them to move widthwise of the pressure box when they are adjusted forward and back in the converging guideways 17, 19.

Cut in the plate 21 is a slot 33 which is parallel to the guideway 17; and cut in the plate 23 is a slot 35 which is parallel to the guideway 19. A bolt 37, carried by the cap 9, 40 extends up through both of these slots and has threaded upon its upper end a nut 39 provided with a handle 41. These slots and the bolt help to guide the plates when they are being adjusted, and the nut furnishes means 45 for locking them in adjusted position. After this nut has been loosened, the plates 21, 23 may be adjusted forward and back, to change the size of the recess outlined by the plates, by turning a hand wheel 42.

50 This hand wheel is fast to a shaft 43 which is rotatably mounted in bearings carried by the cap 9 and has two pinions 45, 47 which mesh respectively with racks 49, 51 cut in the under face of the plate 23. Connected 55 to the inner end of the shaft by a universal joint is one end of a short shaft 53 the other end of which is connected by a second universal joint to one end of a shaft 55. This shaft, like the shaft 43, is mounted in bearings carried by the cap 9 and has two pin-

ions 57, 59 which mesh respectively with racks 61, 63 cut in the under face of the plate 21. In order to aid in guiding the plates 21 and 23 in their movements, a guide member 65 carried by the cap 9 engages an edge of 70 the plate 21, and a similar guide member 67 engages an edge of the plate 23. With this construction the plates 21, 23 may be adjusted simultaneously in converging or diverging paths by turning the hand wheel 42 and may 75 be locked in adjusted position by means of the nut 39.

Cooperating with the plates 21, 23, which are adapted to extend around the toe portion of a shoe, is another pair of plates 69, 71 80 which are adapted to extend around the heel portion of the shoe. These plates are mounted respectively in guideways 73, 75 in the cap 9, are guided in part by a bolt 77 and slots 79, 81 in their converging and diverging 85 paths, are held in contact and at the same time permitted widthwise movement by a bolt 83, nut 85, washer 87 and slot 89, and may be adjusted simultaneously by turning a hand wheel 91. In short the plates 69, 71 90 are mounted and are adjustable in substantially the same manner as are the plates 21, 23.

The inner edges of the plates 69, 71 95 cooperate to provide a generally U-shaped recess; and the two U-shaped recesses,—that formed by the plates 21, 23 and that formed by the plates 69, 71,—are arranged to form a closed elongated opening having rounded ends through which the lower portion of a 100 shoe may be pushed by the jack. The smaller end of the plate 69 overlaps the smaller end of the plate 21; and their inner edges which form part of one side of the elongated opening are in register. The smaller end of the plate 23 overlaps the smaller end of the plate 71; and their inner edges are also in register. With this construction the hand wheels 42, 91 may be turned to vary the size of the 105 elongated opening while maintaining its general shape unchanged. This opening is somewhat narrower at the end which receives the heel end of the shoe than it is at that end which receives the toe end of the shoe, the sides of the opening diverging gradually 110 from the end which receives the heel to the end which receives the toe.

The purpose of these plates, as has been 115 explained, is to prevent the diaphragm from ballooning up about the shoe when water is forced into the pressure box and to limit the flexing of that portion of the diaphragm which is not in engagement with the shoe to a narrow locality surrounding the shoe. In 120 the operation of the machine, the hand wheels 42, 91 are manipulated to adjust the plates to provide an opening of a size just sufficient to permit the lower portion of a shoe of a given size to pass through it. Thereafter 125 that shoe and shoes of sizes which do not 130

differ greatly from it may be operated upon.

Certain subject-matter herein disclosed is also disclosed in applicant's copending applications Serial No. 209,297, filed July 29, 1927, and Serial No. 352,278, filed April 3, 1929; and all subject-matter common to these two applications and the present application is claimed in said two applications.

Although the invention has been set forth as embodied in a particular construction it should be understood that the invention is not limited in the scope of its application to the particular construction which has been shown and described.

Having thus described my invention, what I claim as new and desire to secure by Letters Patent of the United States is:

1. The combination with a pressure box one wall of which comprises a flexible diaphragm, of two pairs of plates shaped to enclose an opening through which a shoe may pass, a member manipulation of which adjusts one pair of plates, and a second member manipulation of which adjusts the other pair.

2. The combination with a pressure box one wall of which comprises a flexible diaphragm, of two pairs of plates shaped to enclose an opening through which a shoe may pass, a member manipulation of which adjusts one pair of plates, a second member manipulation of which adjusts the other pair, and means for locking one member of each pair from movement with respect to the other member.

3. The combination with a pressure box one wall of which comprises a flexible diaphragm, of two pairs of plates adapted to enclose an elongated opening which is wider at one end than the other, and means for adjusting the members of the pairs in paths which are oblique to each other.

4. The combination with a pressure box one wall of which comprises a flexible diaphragm, of two pairs of plates located above the diaphragm and adapted to enclose an elongated opening which is wider at one end than at the other, and means for adjusting the members of the pairs in paths which are oblique to each other.

5. The combination with a pressure box one wall of which comprises a flexible diaphragm, of two pairs of converging guideways located above the diaphragm, and two pairs of plates the members of each pair having their outside edges located in a guideway, a portion of the inner edges of the members of each pair being shaped to provide between them a recess.

6. The combination with a pressure box one wall of which comprises a flexible diaphragm, of two pairs of converging guideways located above the diaphragm, two pairs of plates the members of each pair having their outside edges located in a guideway, a

portion of the inner edges of the members of each pair being shaped to provide between them a recess, and means for adjusting the plates along the guideways.

7. The combination with a pressure box one wall of which comprises a flexible diaphragm, of two converging guideways, and two cooperating plates each having its outer edge located in a guideway the inner edges of said plates being shaped to provide between them a recess.

8. The combination with a pressure box one wall of which comprises a flexible diaphragm, of two converging guideways, two cooperating plates each having its outer edge located in a guideway the inner edges of said plates being shaped to provide between them a recess, and means for adjusting the plates along the guideways to vary the size of the recess.

9. The combination with a pressure box one wall of which comprises a flexible diaphragm, of two converging guideways, two cooperating plates each having an edge located in a guideway, cooperating edges of the plates being shaped to provide a recess between them, and a slip connection between the plates constructed and arranged to permit the plates to overlap each other more or less as they are moved toward or away from the converging ends of the guideways.

10. The combination with a pressure box one wall of which comprises a flexible diaphragm, of a plurality of members located above the diaphragm for controlling deflection of the diaphragm and adapted to enclose an opening through which a shoe may pass, and means for adjusting each member laterally and longitudinally of the opening to vary the size of the opening while maintaining the shape of the opening substantially unchanged.

11. The combination with a pressure box one wall of which comprises a flexible diaphragm, of two pairs of plates for controlling upward deflection of the diaphragm, said plates being shaped to enclose an opening through which the bottom of a shoe may pass, means for adjusting the plates to vary the size of the opening, and means for locking the plates in adjusted position.

In testimony whereof I have signed my name to this specification.

SIDNEY J. FINN.
